UNITED STATES PATENT OFFICE.

ONESIME E. MICHAUD, OF ST. LOUIS, MISSOURI.

ATTACHMENT FOR SHOTGUNS.

No. 906,443.

Specification of Letters Patent.

Patented Dec. 8, 1908.

Application filed March 7, 1908. Serial No. 419,615.

To all whom it may concern:

Be it known that I, ONESIME E. MICHAUD, a citizen of the United States, and a resident of the city of St. Louis and State of Missouri, have invented a new and useful Improvement in Attachments for Shotguns, of which the following is a specification.

My invention relates to shotguns and has for its principal object to provide for the attachment of a removable choke muzzle thereto.

It consists in the construction and arrangements of parts hereinafter described and claimed.

15 In the accompanying drawing, which forms part of this specification, and wherein like symbols refer to like parts wherever they occur, Figure 1 is an elevation of the forward end of a double-barreled shotgun with my choke muzzle attached thereto; Fig. 2 is a cross section thereof on the line 2—2 of Fig. 1; Fig. 3 is a longitudinal section along the midrib on the line 3—3 of Fig. 2; Fig. 4 is a detail view of a modified form; Fig. 5 is a 20 plan view; Fig. 6 is a longitudinal sectional view along the line 6—6 of Fig. 5, the choke muzzle being detached and its locking device being shown in unlocked position.

The gun is a double-barreled gun of ordinary type. Close to the muzzle, the midrib 1 between the barrels 2 is provided with two lugs 3, 4 one on the top and the other on the bottom. The upper lug 3 may be arranged to serve as a sight. The rear surface of each 35 of these lugs is slightly tapered or curved convexly.

The removable choke muzzle is a short member comprising a midrib 5 and two choke barrels 6. The rear end of this choke muzzle 40 is finished to form a butt-joint with the gun; that is, to fit flush against the end of the gun barrels, with its choke bores continuous with the bores of the gun barrels.

The lower surface of the midrib of the 45 choke muzzle has a locking member 7 secured thereto or integral therewith. This locking member projects rearwardly and has a slot therein which fits over the lower lug 4 of the midrib of the gun. The slot is so shaped and 50 located that the entire surface of its rear wall bears against the rear end of said lower lug, when the choke muzzle is jammed against the front end of the gun barrels.

On the upper surface of the midrib of the 55 choke muzzle is mounted a second locking member 8 which likewise is provided with a

slot 9 adapted to coöperate with the lug or sight 3 on the upper end of the midrib of the gun. This locking member is preferably a strong spring which is fastened near its front 60 end to the midrib of the muzzle, having its projecting rear end movable transversely, that is, perpendicularly to the midrib. This spring locking member has a vertical slot 10 in its middle portion. The sides of this slot 65 10 are provided with lugs 11 which constitute a support for a horizontal pintle 12; and on this pintle is mounted a cam lever 13. The short end of this lever is of such length that, when the muzzle is locked on the gun the 70 turning of the lever perpendicularly to the midrib will lift the locking member clear of the sight or locking lug 3 of the gun. Normally, the lever lies with its lower edge flush with or resting on the upper surface of the 75 midrib, the outer end 14 of its long arm being bent up slightly to facilitate its manipulation by the finger.

The rear end of the locking slot 9 of the spring member 8 is shaped and positioned to 80 fit slidingly against the rear face of the sight or locking lug 3. For this purpose, the surface of said rear wall has a curvature whose center is approximately at the point where the spring is mounted. The purpose of the 85 curvature is to allow the locking member to make a tight joint and still permit the locking spring to be elevated clear of the lug.

On the rear end of the midrib of the choke muzzle is a lug 15, which is preferably of such 90 length that its rear end abuts squarely against the sight or locking lug 3 on the gun. The front end of this locking lug 15 has a concave 95 curve against which fits the short arm of the cam lever, when said cam lever is in its normal position. By this arrangement, the cam lever serves as a locking member to prevent the accidental lifting of the locking spring out of engagement with the lug 3.

The operation of mounting the choke 100 muzzle is as follows: Assuming that the gun is in a horizontal position, the choke muzzle is inclined downwardly and its lower member is engaged with the lower lug of the gun. Then the cam lever is turned up perpendicular 105 to the midrib of the choke muzzle, and the choke muzzle is tilted up until it fits squarely against the end of the gun. Then the cam lever is depressed to lie flush against the upper surface of the midrib of the choke 110 muzzle, and have its rear end fit in the concave or undercut portion of the lug on the

midrib. When the cam lever is turned, the spring locking member automatically bears down to engage with the sight or upper locking lug on the gun. On account of the tightness of the fit, it may be necessary to force or press the locking member into its ultimate locking position. In order to dismount the choke muzzle, it is merely necessary to raise the cam lever, thereby disengaging the locking spring, and then tilt or swing the choke muzzle downwardly to disengage the lower portion thereof.

It is noted that a gun adapted for the use of my attachment does not have its appearance marred, as the upper locking lug may be utilized as a sight, and the lower locking lug is inconspicuously located. When the choke muzzle is mounted, the upper locking members merely have the appearance of a long sight.

Obviously, my device admits of considerable modification without departing from my invention, and therefore I do not wish to be limited to the specific construction shown and described.

What I claim is:

1. A double-barreled shotgun having lugs on the top and bottom of its midrib, and a choke muzzle therefor having slotted locking members arranged to coöperate with said lugs the upper locking lug constituting a sight for the gun.

2. A double-barreled shotgun having lugs on the top and bottom of its midrib, and a choke muzzle therefor having slotted locking members arranged to coöperate with said lugs, one of said members being a spring whose rear end is movable transversely and the lug on the top of the midrib constituting a sight for the gun.

3. A double-barreled shotgun having locking lugs on the top and bottom of its midrib, and a choke muzzle therefor, said

choke muzzle comprising a midrib having a slotted member adapted to interlock with one of said lugs, and a slotted member adapted to interlock with the other lug, said last mentioned slotted member being provided with means for moving it transversely and the lug on the top of the midrib constituting a sight for the gun.

4. A double-barreled shotgun having lugs on the top and bottom of its midrib, and a choke muzzle therefor having slotted locking members arranged to coöperate with said lugs, the rear portion of one of said locking members being transversely movable, said last mentioned locking member having a cam adapted to move it transversely.

5. A double-barreled shotgun whose midrib has lugs on its top and bottom, a choke muzzle therefor having a midrib, a slotted member adapted to coöperate with one of said lugs, a second slotted member adapted to coöperate with the other lug and having its rear end transversely movable, and a cam lever pivotally mounted on said last mentioned slotted member and arranged to bear against the upper surface of the said midrib.

6. A double-barreled shotgun whose midrib has lugs on its top and bottom, a choke muzzle therefor having a midrib, a slotted member adapted to coöperate with one of said lugs, a second slotted member adapted to coöperate with the other lug and having its rear end transversely movable, a lug on the midrib of said choke muzzle, and a cam lever pivotally mounted on said last mentioned slotted member and arranged to bear against the forward end of said last-mentioned lug.

ONESIME E. MICHAUD.
